UNITED STATES PATENT OFFICE

JOHN D. KARLE, OF ROSELLE PARK, NEW JERSEY, ASSIGNOR TO DIEHL MANUFACTURING COMPANY, OF ELIZABETH, NEW JERSEY, A CORPORATION OF NEW JERSEY

DYNAMO-ELECTRIC MACHINE

Application filed June 30, 1928. Serial No. 289,333.

This invention relates to dynamo-electric machines, more particularly of the single-phase motor type having a commutator, with short-circuited brushes and a speed-responsive commutator short-circuiting mechanism, adapting the motor for repulsion operation in starting and induction operation after a predetermined speed has been attained.

An object of the invention is to provide a simplified and efficient mechanism for lifting the brushes from the commutator, after the motor has been started, to avoid unnecessary brush-wear.

Another object of the invention is to provide for quietness and freedom from wear of the parts when the motor is running. A further object of the invention is to provide a brush-lifting mechanism having minimum wearing pressures upon the relatively rotating parts in starting, thus increasing the useful life of the parts. Still further, the invention has for an object to provide a free floating support for the commutator short-circuiting disk permitting it to adapt itself to any irregularities in the commutator.

According to the present improvement there is provided a brush-lifting member which is adapted to exert a yielding pressure in one direction only from a position of rest, in which direction it engages and lifts the brush. The speed-responsive commutator short-circuiting means is arranged to kick-off or initiate the movement of said member from its position of rest. Due to this arrangement, the action of the speed-responsive mechanism is independent of the brush-lifting mechanism and, consequently, the speed-responsive device has to press but lightly and momentarily against the brush-lifting mechanism, to trip the latter into action.

In the accompanying drawings, Fig. 1 is a longitudinal sectional view of an electric motor embodying the invention; the parts of the brush-lifting mechanism being in starting position. Fig. 2 is a similar view of the brush-lifting elements of Fig. 1 in running position. Fig. 3 is an end view of the motor with the parts in starting position. Fig. 4 is a longitudinal section on the line 4-4, Fig. 1. Fig. 5 is a disassembled perspective

view of the removable brush and brush-shank elements of Fig. 4, and Fig. 6 is a view, similar to Fig. 2, of a modification of the invention.

According to the preferred embodiment of the invention illustrated in Figs. 1 to 5, inclusive, 1 represents the motor frame, 2 the field, 3 the armature and 4 the commutator carried by the armature-shaft 5. Fixed to the shaft 5 is a carrier 6 having radially disposed cylindrical slideways 7 for the cylindrical weights 8 having conical outer ends 9. Slidably mounted on the shaft 5, between the carrier 6 and the commutator 4 is the disk 10 which is dished to provide a conical portion 11 overhanging the conical outer ends of the weights 8. The disk 10 is also formed with a flat rim 12 disposed in a plane normal to the shaft 5. The disk 10 is urged by the spring 13 toward the carrier 6 and, when the motor is at rest, the disk 10 engages the narrow raised ring-shaped seat 14 on the carrier 6, closely adjacent the shaft 5.

Fixed to the disk 10 are studs 15 which pass through somewhat larger apertures in the commutator short-circuiting disk 16 and are surrounded by springs 17 disposed between the disks 10 and 16 and yieldingly urging the disk 16 into engagement with the heads 18 of said studs. The disk 16 is of the usual radially slotted construction enabling it to bear upon the ends of the commutator segments and effectively short-circuit the latter when pressed thereagainst by the action of the centrifugal weights 8 upon the conical portion 11 of the disk 10. The disk 16 is free to float or tilt relative to its carrier disk 10 and adapt itself to any irregularities in the commutator, or to bear evenly upon the commutator despite any unevenness in the running of the disk 10.

The end-bonnet 1' of the motor-frame 1 is formed with a pair of bosses 19 each of which is bored radially of the commutator 4 to receive a brush-tube bushing 20 in which is fixed a brush-tube 21 on the lower end of which is clamped a terminal lug band 22 for the usual brush short-circuiting connection 23. Slidably mounted in each brush-tube 21 is a brush-holder tube 24 constituting a brush-shank in the socketed inner end of which a

brush 25 is secured by a screw 26. The brush-holder tube 24 may be considered as a part of the brush 25, since it is in fixed relation with the latter.

Disposed within the brush-tube 21 is the brush-spring 27 which at its inner end is connected to the brush 25 and at its outer end presses the terminal washer 28 of the brush pig-tail 29 against the cap-screw 30 which is threaded into and closes the outer end of the brush-tube 21. A pin-screw 31, threaded into the boss 19 and passing through the bushing 20 and brush-tube 21, enters a longitudinal slot 32 in the brush-shank 24. This pin fixedly positions the bushing 20 and brush-tube 21 in the boss 19 and permits the brush-shank 24 to freely perform endwise sliding movements, without rotation. The slot 32 is open at its inner end to permit withdrawal of the brush from the brush-tube 21. At the outer end of the slot 32 there is a shoulder 33 which is adapted to engage the pin-screw 31, when the brush 25 has worn sufficiently, and prevent the inner end of the brush-shank 24 from scraping the commutator. The brush-shank 24 is also formed with a shoulder 34 for engagement by the brush-lifting lever 35 which is fulcrumed at 36 on the ear 37 extending inwardly from the boss 19.

The brush-lifting lever 35 is cut away at 38 to embrace the rim 12 of the speed-responsive disk 10 and is also formed with a V-shaped notch 39, to receive the conical end 40 of the plunger 41 which is pressed inwardly by the spring 42. The inner conical end of the plunger 40 is flattened or squared-off at 43 to rest upon the hump 44, Fig. 1, at one side of the V-notch 39 in the lever 35, when the motor is at rest, without tendency to impart motion to the lever 35. In this, the set position of the parts, the brush 25 is bearing upon the commutator, the lever 35 is spaced from the shoulder 34, and the rim 12 of the disk 10 is in engagement with one wall of the notch 38 and spaced from the opposite wall a distance substantially equal to the distance of the short-circuiting disk 16 from the commutator, and full power is stored in the spring 42.

When the motor is started and attains a predetermined speed, the centrifugal action of the weights 8 upon the disk 10 forces the latter towards the commutator and causes the short-circuiting disk 16 to be pressed against the commutator. In this movement of the disk 10, its rim 12 is carried across the open mouth of the notch 38 without disturbing the position of repose of the lever 35. After the short-circuiting of the commutator is effected, the further movement of the disk 10 in compressing the springs 17 and 18, causes its rim 12 to press against the inner wall of the notch and kick off or trip the lever 35 into action by swinging it sufficiently to carry the hump 40 off of the flat inner end of the plunger 41, whereupon the spring 42 in pressing the

plunger 41 into the V-notch 39, swings the lever 35 to the predetermined position shown in Fig. 2 with a snap action and lifts the brush 25. The lever 35 is thus adapted to exert a yielding pressure upon the brush in one direction only from its position of repose, Fig. 2. The speed-responsive disk 10 initiates the movement of the lever 35 from its position of repose, and this requires but a momentary and light pressure of the disk 10 upon the lever 35, whereby the timing of the brush-lifting action of the lever 35 is not disturbed, relative to the time of short-circuiting of the commutator, by wear of the inner wall of the notch 38 upon the rim 12 of the disk 10. In the running position of the parts, Fig. 2, the rim 12 of the disk 10 floats quietly in the notch 38 without engaging the walls thereof.

When the power is cut off from the motor and the latter slows down, the recovery spring 13 forces the disk 10 toward the right, Fig. 2, and withdraws the commutator short-circuiting disk 16 from the commutator 4; at the same time restoring the lever 35 to or resetting it in its initial position of repose and storing power in the spring 42 for the next starting operation. The spring 13 is strong enough to overcome the resistance of the brush-lever actuating springs 42, which latter are strong enough to overcome the resistance of the brush-springs 27.

In the modification shown in Fig. 6, the parts carried by the motor-shaft 5 are identical with those shown in Figs. 1 to 5, inclusive. Also, the brush and its holder, the brush-tube, bushing, stop-screw, and brush-spring are identical with the like parts previously described. The modification is in the brush-lifting lever 35' which is pivoted at 36' on the ear 37' rigid with the boss 19'. The lever 35' is actuated by the spring 42' which is coiled about the screw 36' and anchored at its opposite ends to the lever 35' and screw 36'. In the position of rest shown in Fig. 6, the lever 35' is held out of engagement with the shoulder 34 of the brush-shank, with full power stored in the spring 42', by the spring 13 which presses the disk 10 against the short arm 48 of the lever 35'. When the motor is started and the disk 10 moves toward the commutator, the lever 35' cannot follow the disk 10 as it is arrested by engagement of the pin 45 with the shoulder 46' of the spring-pressed latch-lever 46 fulcrumed at 47 on the ear 37'. After the short-circuiting disk 16 is pressed into engagement with the commutator, the disk 10, in its further movement, trips or kicks off the latch-lever 46 and releases the lever 35' which acts under the influence of its spring 42' to lift the brush.

The arm 48 of the lever 35' is engaged by the rim 12 of the disk 10 in re-setting the lever 35' when the motor is slowing down to

a stop. The lower end of the latch-lever 46 is spaced from the end of the lever-arm 48 a distance permitting movement of the short-circuiting disk 16 into engagement with the 5 commutator before release of the lever 35' by movement of the latch-lever 46.

The brushes 25 are initially of such length that they are lifted but a short distance from the commutator by the action of the levers 10 35 or 35'. As the brushes wear, the shoulders 34 are correspondingly lowered and the brush-lift increased. The shoulder 33 is preferably arranged to strike the stop-pin 31 before the brushes wear sufficiently to let the 15 shoulder 34 down upon the levers 35 or 35' in the initial positions of repose of the latter.

Having thus set forth the nature of the invention, what I claim herein is:

1. In an electric motor, an armature having 20 a commutator, an armature shaft, speed-responsive commutator short-circuiting means including a disk movable lengthwise of the armature shaft, a brush yieldingly engaging the commutator, a brush-lifting lever having 25 a notch entered by the rim of said disk, a spring for moving said lever in a direction to lift the brush, and means independent of said disk for detaining said lever in one extreme position with full brush-lifting power 30 stored in said spring.

2. In an electric motor, an armature having a shaft and commutator, a speed-responsive disk movable lengthwise of the motor-shaft, a commutator short-circuiting disk disposed 35 between the speed-responsive disk and the end face of the commutator, a plurality of headed pins mounted on one of said disks and passing through apertures in the other disk, said pins being spaced equidistantly around 40 the armature shaft, and a plurality of coil springs each surrounding a respective one of said pins between said disks.

3. In a dynamo-electric machine, rotary current-carrying means, a brush, a brush-spring urging said brush into engagement 45 with said means, brush-lifting mechanism including a brush-lifting element and a brush-lifting spring for actuating said brush-lifting element in a direction to lift the brush 50 against the pressure of the brush-spring, a speed-responsive device, means independent of the speed-responsive device for detaining the brush-lifting element in a position of repose, with full brush-lifting power stored in 55 the brush-lifting spring, while the machine is at rest, and a connection between the speed-responsive device and the brush-lifting mechanism for tripping the latter into action.

4. In a dynamo-electric machine, rotary 60 current-carrying means, a brush, a brush-spring urging said brush into engagement with said means, a speed-responsive device, a self-contained spring-actuated brush-lifting mechanism the parts of which are maintained 65 in a set position of repose, independently of

the associated parts of the speed-responsive device, with full brush-lifting power stored in the brush-lifting spring, the action of said brush-lifting mechanism being initiated by the speed-responsive device when the latter 70 attains a predetermined speed.

5. In a dynamo-electric machine, rotary current-carrying means, a brush yieldingly engaging said rotary current-carrying means, a spring-energized brush-lifting mechanism 75 settable in a position of repose with full brush-lifting power stored in said spring, and speed-responsive means for kicking off said spring-energized brush-lifting mechanism at a predetermined speed.

6. In an electric motor, an armature having a commutator, an armature shaft, speed-responsive commutator short-circuiting means including a disk movable lengthwise of said armature-shaft, a brush yieldingly engaging 85 the commutator, a brush-lifting lever connected to be moved in either direction by said disk, a spring for moving said lever in a direction to lift said brush, and means independent of said disk for detaining said lever 90 in one extreme position with full brush-lifting power stored in said spring.

In testimony whereof, I have signed my name to this specification.
